UNITED STATES PATENT OFFICE.

HARRY S. UBER, OF PHILADELPHIA, PENNSYLVANIA.

PHONOGRAPH.

1,426,128.

Specification of Letters Patent. Patented Aug. 15, 1922.

Application filed September 4, 1920. Serial No. 408,342.

To all whom it may concern:

Be it known that I, HARRY S. UBER, a citizen of the United States, residing at Philadelphia, in the county of Philadelphia and State of Pennsylvania, have invented certain new and useful Improvements in a Phonograph, of which the following is a specification.

My invention relates to improvements in a phonograph, or talking machine, and the object of the invention is to provide a device, controlled by the tension of the motor-spring, for showing when the latter should be rewound; a further object of my invention is to provide a stop adapted to engage the control-lever and prevent the latter from being shifted to start the machine when the motor-spring is partially run down and the tension on the motor-spring is not sufficient to operate the machine for a period of time long enough to play one full record, thus my invention will obviate the annoyance of the machine stopping during the playing of a record. These together with various other novel features of construction and arrangement of the parts constitute my invention.

Referring to the accompanying drawings; Fig. 1, is an end elevation of a portion of a phonograph embodying my invention; Fig. 2, is a plan view of Fig. 1; Fig. 3, is a side elevation of Fig. 2; Fig. 4, is a vertical section on line 4—4 Fig. 3, showing the stop pin in a position to hold the control lever in the "off" position; and Fig. 5, is a perspective of a modified form of my invention.

Referring to the drawings, in which like reference characters refer to like parts, 1 represents the removable portion of the casing of a phonograph of any well known type. A spring motor is secured to the casing and consists of the housing 2, the winding shaft 3, on which are mounted the motor-spring casings 4 and 5 and to which shaft one end of the motor-spring 6 is attached. The disk table 7 is adapted to be rotated by the gear wheel 8 on the motor-spring casing 5. The winding shaft 3 has secured thereon a ratchet wheel 10, which is engaged by a pawl 12 for preventing the shaft 3 from turning by the action of the motor-spring 6.

The pawl 12, heretofore has been pivotally mounted upon a pin or shaft secured in the housing 2. In the present invention the pawl is mounted upon a movable member 14 adapted to be moved in one direction by the tension of the motor-spring 6 and in the op-

posite direction by a counter spring 16 having less tension than the motor-spring, when the latter is partially wound, so that the counter spring 16 will actuate the movable member 14 at a predetermined point in the unwinding of the motorspring. The movable member 14 is associated, through levers 26, 25, 30 and 32, with a stop pin 18 adapted to be moved into the path of the control member or starting and stopping lever 20 and thus prevent the latter from being shifted to start the machine. The counter spring 16 is made with sufficient power to move the movable member 14 against the action of the motor-spring 6 at a certain place in the unwinding of the motor-spring.

If the motor will run the machine, as for example, a sufficient time to play three full records and about half of a fourth record, the counter spring 16 is set so as to overcome the tension of the motor-spring during the playing of the third record. The movable member is thus shifted by the counter spring 16 and the stop pin 18 in turn is moved into a position which will allow the control member 20 to be moved to stop the machine at the end of the playing of the third record. The pin 18 will lock the control member 20 in the "off" position, so that the machine can not be again started for playing the fourth record until the motor is again wound up and the increased tension on the motor-spring 6 shifts the movable member 14 against the action of the counter spring 16 and the movable member 14 in turn withdraws the pin 18 out of the path of the control member 20.

The movable member 14, preferably consists of a U-shape frame, more clearly shown in Fig. 5, which is loosely mounted upon the shaft 3 and is free to rotate thereon between stops 21 and 22 secured in the housing 2. The frame 14 embraces the ratchet wheel 10, and has secured therein a shaft 23, upon which latter is pivotally mounted the pawl 12, which engages the ratchet wheel 10 and prevents the shaft 3 from turning in a direction which would allow the motor-spring to unwind. The shaft 23 extends beyond the frame 14 and forms a convenient place for attaching one end of the counter spring 16. The opposite end of said spring is attached to the housing 2 as clearly shown in the drawings.

A link or connecting rod 25 is pivotally attached to the U-shaped frame 14, in any

suitable manner, preferably to the end of an arm 26 secured to, or forming part of, the frame 14. A rock-shaft 28 is mounted in bearings 29 upon the housing 2, and is provided at one end with an arm 30 to which the connecting rod 25 is attached. The opposite end of the rock-shaft 28 is provided with a spring-plate 32 adapted to lift the pin 18, slidably mounted in a sleeve 19 secured 10 in the casing 1.

The pin 18 is adapted to engage the control member 20 and hold it in the "off" position, as shown in dotted lines Fig. 2, in which position the control member 20 engages the 15 disk table 7 and holds the machine from operating.

The pin 18 is located upon the casing 1 in alignment with the control member 20, when the latter is in the "on" position, as shown 20 in full lines Fig. 2. The pin 18, when lifted by the spring-plate 32, will strike against the underside of the control member 20, which latter prevents the pin from being lifted to the full extent of its movement. The spring- 25 plate 32 will yield and assume the position shown in dotted lines Fig. 1. The control member 20 is therefore free to slide over the head of the pin 18 and be moved either by hand or by the automatic stopping lever 34, 30 from the "on" to the "off" position. When the control member 20 is thus moved to the "off" position the pin 18 will be lifted to its full extent, by the spring-plate 32, as shown in Fig. 4, and will occupy a place in 35 the path of the control member 20, thus preventing the control member 20 from being shifted to the "on" position until the motor is again wound sufficiently to cause the tension of the motor-spring 6 to actuate the movable 40 member 14 against the action of the counter spring 16, and thus move the parts into the position shown in full lines Fig. 1, in which the pin 18 has fallen out of the path of the control member 20 and the latter is free to be moved by hand to again start the machine. 45

The movable member 14 may be connected with a pointer 35, as shown in Fig. 5, for indicating when the motor-spring should be wound. The movable member 14 is connected by a link 36 to the arm 37 on a rock-shaft 38 mounted in the casing 7 of the machine.

The hand or pointer 35 is secured to the rock-shaft 38 and is adapted to be moved adjacent to a dial 39 having suitable indicating marks thereon showing the relative 55 tension of the motor-spring.

Having thus described my invention, I claim and desire to secure by Letters Patent:

1. A phonograph having in combination a motor, a casing, a control member for starting and stopping the motor, a pin slidably mounted in the casing in alignment with the control member when the latter is in the starting position, a flexible member for lifting the pin against the control member and for moving the pin into the path of the control member when the latter is in the stopped position and means actuated by the motor for moving the pin through the medium of the flexible member. 70

2. A phonograph having in combination a motor-spring; a control member for starting and stopping the phonograph, a pin forming a stop to hold the control member against starting movement, a sleeve in which the pin is slidably mounted, a yielding member for lifting the pin into the path of the control member, a rock-shaft in which the yielding member is mounted, and mechanism controlled by the relative tension of the motor-spring for moving the rock-shaft. 75

3. A phonograph having in combination a motor-spring, a winding-shaft for said motor-spring, a pawl to hold the winding-shaft against unwinding movement, a movable member upon which the pawl is fulcrumed, a spring to move the movable member against the action of the motor-spring when the latter is partially run down, a connecting rod pivotally attached at one end to the movable member, a rock-shaft actuated by the connecting rod, an arm upon said rock-shaft, a pin actuated by the said arm and a control lever for starting and stopping the phonograph adapted to be engaged by said pin and held against starting movement when the said movable member has been shifted against the reduced tension of the motor-spring. 90

In testimony whereof I affix my signature. 100

HARRY S. UBER.
